UNITED STATES PATENT OFFICE.

CHARLES HAMMER, OF NEW YORK, N. Y., ASSIGNOR OF ONE-THIRD TO
CHRISTIAN H. WERNER, OF NEW YORK, N. Y.

BOTTLE-CLOSURE.

No. 821,488.

Specification of Letters Patent.

Patented May 22, 1906.

Application filed July 28, 1905. Serial No. 271,613.

To all whom it may concern:

Be it known that I, CHARLES HAMMER, a citizen of the United States of America, residing at New York, in the county of New York and State of New York, have invented new and useful Improvements in Bottle-Closures, of which the following is a specification.

This invention relates to bottle-closures. The objects of the invention are to improve the construction of such devices; furthermore, to increase their efficiency in operation and to decrease the expense attending their manufacture and application to a bottle.

With the foregoing and other objects in view, which will appear as the description proceeds, the invention resides in the combination and arrangement of parts and in the details of construction hereinafter described and claimed as a practical embodiment thereof.

In the accompanying drawings, forming part of this specification, Figure 1 is a side elevation, partly in section, of a bottle provided with a cap constructed in accordance with the present invention. Fig. 1^a is a side view of the cap employed in the construction shown in Fig. 1. Fig. 2 is a similar view showing a slightly-modified construction. Fig. 2^a is a side view of the cap employed in the construction shown in Fig. 2. Fig. 3 is a vertical section of another modified construction. Fig. 4 is a view similar to Fig. 3 with the parts separated. Fig. 5 is a side elevation showing the invention in connection with a jar. Fig. 6 is a vertical section of the construction shown in Fig. 5.

Like reference-numerals indicate corresponding parts in the different figures of the drawings.

The reference-numeral 1 indicates a bottle or jar which may be of any suitable form, size, shape, and construction. Bottle 1 is formed adjacent to the upper end thereof with an annular rib or shoulder 2. Extending upward from the rib or shoulder 2 is a plurality of separated spiral threads, such as 3 4. Each of the threads 3 4 is adapted to be engaged by an inward projection upon a cap, such as 5, which may be crimped or roughened around its periphery, as indicated at 6, in order to facilitate its application to and removal from the bottle. The inward projec-

tions on the cap 5 preferably are produced by notching or stamping inward a portion of the lower edge thereof, as indicated at 7. Each of the notches 7 preferably is formed with an inclined upper end, as indicated clearly in Figs. 1, 2, and 6, the incline of the upper end of the notch being the same as the incline of the shoulder or thread 3 4, which said notch is intended to engage in applying the cap to a bottle. The cap 5 is formed in its top with a depression, such as 8, and is provided interiorly with a disk, such as 9, of any suitable material, the disk 9 being adapted to be forced closely against the upper end of the bottle by means of the depression 8 in order to close said bottle in an air-tight manner.

The construction illustrated by Fig. 2 is exactly the same as that illustrated by Fig. 1, except that the bottle is provided with two more closely-related separated spiral threads 10, and the cap 5 is formed with an additional number of notches 11, having inclined upper ends to engage said threads. It will be apparent that the invention can be carried out by using two or in some cases even more separated threads.

It will be observed from Figs. 1 and 2 that the separated threads extend upward from the annular rib or shoulder 2. For this reason it is only necessary to give the cap a partial revolution in order to lock it in position upon the bottle. Furthermore, it will be observed that when the cap is reversely rotated the notches will ride up the threads, so as to release the cap quickly from its engagement with the bottle.

The constructions illustrated in Figs. 3 to 6, inclusive, are practically the same as those shown in Figs. 1 and 2, except that the bottle or jar is rabbeted, as indicated at 12, to receive an inner seal or disk, such as 13. The disk 13 may be either flat, as indicated in Figs. 3 and 4, or dished, as indicated in Figs. 5 and 6. When a dished disk is employed, the depression 8 strikes against the dished portion of the disk so as to flatten the same and cause it to expand in diameter, so as to form an air-tight seal in the upper end of the bottle or jar.

It is well known that in using a jar or bottle having the ordinary form of single spiral thread it is necessary that the cap be also threaded. Furthermore, in applying the

old form of threaded cap it is necessary to give the same a plurality of revolutions in order to apply it to the bottle. According to the present invention, the expense and time 5 consumed in forming a cap with screw-threads is avoided, and a great saving of time is effected in applying the cap after the contents of the jar or bottle have been inserted.

10 The improved bottle-closure of this invention is strong, simple, durable, and inexpensive in construction, as well as thoroughly efficient in operation.

Changes in the precise embodiment of invention illustrated and described may be made within the scope of the following claims without departing from the spirit of the invention or sacrificing any of its advantages.

It will be observed that in each instance 20 each cap is provided with one or more in-punched locking projections, said projections being formed at the extreme lower edge of the cap, each projection having an inclined upper wall and being minus a lower wall, the

25 exterior recess formed in the flange of the cap by each projection opening at its lower end through the edge of the cap. By this construction less resistance is encountered to the action of the die in forming the locking

30 projections and less care is required in finishing the cap, as it is not necessary to take measures to prevent bulging or outspreading of the metal, such as would be necessary in forming the projections wholly above the 35 upper edge of the cap, in which action there would be a tendency of the metal below the lower end or base wall of the projection to bend outward on the inward punching of the metal by the die. Furthermore, the less re-

40 sistance encountered in forming my improved construction of the projections minimizes fracture of the metal and reduces wastage from the formation of imperfect caps. Another advantage over a structure of the char-

45 acter referred to in bringing the projections as close down to the edge of the cap as possible which my construction secures is that the lower ends of the spiral threads may be arranged in closer contiguity to the shoulder 2,

50 thus enabling the height of the neck portion above the shoulder on which said threads are formed to be decreased without decreasing the length of the threads and the degree of movement of the cap.

55 It will also be observed that the separated spiral threads connect at their lower ends with the shoulder 2. By this means stops are formed at the juncture of each thread with the shoulder to be engaged by the pro-

60 jections on the cap to limit the turning movement of the cap downward on the neck. As a result, the formation of spaces which will permit the projections to ride beyond the lower ends of the threads is prevented, and 65 liability of the projections becoming hung

against the threads and mutilating or otherwise distorting the cap, so that it cannot be removed, is obviated. As the formation of the projections 11 directly at the lower edge of the cap allows the edge of the cap to come directly into contact with the shoulder 2, it will be apparent that the projections will wedge between the threads and shoulder and securely hold the cap from casual retrograde rotation. By the described disposition of 75 the threads and locking projections all tendency of the upper inclined walls of the projections to be forced downward and distorted by the pressure of the threads will be avoided by the engagement of the lower edge 80 walls of the projections against the shoulder 2, which will thus reinforce said projections and prevent their distortion.

Having thus described the invention, what is claimed as new is—

1. A bottle or jar having a rabbeted portion, a dished disk adapted to fit said rabbeted portion, and a cap adapted to flatten said dished disk to increase its diameter.

2. A bottle or jar having a rabbeted portion, a dished disk adapted to fit into said rabbeted portion, and a cap having a depression in its end adapted to flatten the dished disk to increase its diameter.

3. A bottle or jar having a rabbeted portion, an annular rib, and a plurality of separated spiral threads extending upward from the rib, a dished disk fitted into the rabbeted portion, and a cap having a depression to flatten the dished disk and a plurality of 95 inclined notches in the lower edge thereof to form inward projections to engage the separated threads.

4. A bottle or jar provided with an annular shoulder and a plurality of superposed 105 separated threads connecting at their lower ends with said shoulder, in combination with a cap having one or more in-punched projections at its lower edge to engage said threads, said projections being provided with inclined 110 upper walls having an angular arrangement with relation to the lower edge of the cap conforming to the angular arrangement of the threads with relation to the shoulder, whereby stops are provided at the junction of the 115 threads with the shoulder to limit the turning movement of the cap, the relative angular arrangement of the parts being such as to adapt the cap to be screwed down into close contact with the shoulder so that the inclined 120 upper walls of the projections and basal edges of the inner walls thereof will respectively bear against the threads and shoulder and exert resisting pressures to prevent injury to the projections when the cap is screwed on.

5. A bottle or jar provided with an elongated neck having an annular rib or shoulder and a plurality of superposed separated threads connecting at their lower ends with said shoulder, in combination with a cap hav-

ing one or more inpunched projections at its lower edge to engage said threads, said projections being provided with inclined upper walls having an angular arrangement with 5 relation to the lower edge of the cap conforming to the angular arrangement of the threads with relation to the shoulder, whereby stops are provided at the junction of the threads with the shoulder to limit the turning movement of the cap, the relative angular movement of the parts being such as to adapt the cap to be screwed down into close contact with the shoulder so that the inclined upper walls 10 of the projections and basal edges of the inner walls thereof will respectively bear against

the threads and shoulder and exert resisting pressures to prevent injury to the projections when the cap is screwed on.

6. A bottle or jar having a rabbeted portion, and a plurality of separated threads, a 20 dished disk adapted to fit said rabbeted portion, and a cap having a depression to flatten said disk, and means to engage the separated threads.

In testimony whereof I affix my signature 25 in presence of two witnesses.

CHARLES HAMMER.
